UNITED STATES PATENT OFFICE

111,952

DESIGN FOR A CHAIR SEAT

Willard H. Bond, Jr., East Grand Rapids, Mich.,
assignor to American Seating Company, Grand
Rapids, Mich., a corporation of New Jersey

Application February 5, 1938, Serial No. 74,903

Term of patent 14 years

To all whom it may concern:

Be it known that I, Willard H. Bond, Jr., a citizen of the United States, residing at East Grand Rapids, in the county of Kent and State of Michigan, have invented a new, original, and ornamental Design for a Chair Seat, of which the following is a specification, reference being had to the accompanying drawing, forming a part thereof, in which:

Figure 1 is a front elevational view of the chair seat showing my new design;

Figure 2 is a bottom plan view of the chair seat;

Figure 3 is an enlarged fragmentary elevational view of the fluted side portion of the

front of the seat viewed from line 3—3 of Figure 2;

Figure 4 is an enlarged fragmentary elevational view inverted of the fluted side portion of the rear of the seat viewed from line 4—4 of Figure 2; and

Figure 5 is a sectional view on line 5—5 of Figure 2.

The essential feature of my design resides in the bottom element of the chair seat, shown in full lines.

I claim:

The ornamental design for a chair seat, substantially as shown and described.

WILLARD H. BOND, JR.
